UNITED STATES PATENT OFFICE

PABLO ESCOBEDO, OF EAST ST. LOUIS, ILLINOIS

FLYING MACHINE

Application filed March 12, 1928. Serial No. 261,006.

This invention relates to flying machines of the heavier than air type and its general object is to provide an aerial device that embodies novel features for lifting, propelling, steering and otherwise rendering it translatable and governable. The propelling means embodies in part means simulating in construction that of a fish in which a reciprocable fin or propeller movable over a definite arc and by which the body of the aeroplane is propelled forward and as an aid to a plurality of propellers mounted at the prow and developing a forward propelling movement.

A further object of the invention is to provide an aerial device that employs a plurality of pairs of wings mounted to reciprocate on a horizontal axis and capable of a rotative revulsive movement to vary the lifting power thereof.

20 This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

In the accompanying drawings illustrating the invention:—

Figure 1 is a top plan view of the machine constructed in accordance with my invention.

35 Figure 2 is a bottom plan view thereof.

Figure 3 is a vertical longitudinal median section;

Figure 4 is a section on the plane 4—4 of Fig. 3;

40 Figure 5 is a section on the plane 5—5 of Fig. 3;

Figure 6 is a section on the plane 6—6 of Fig. 3;

45 Figure 7 is an isometric detail of the operating clutch.

Referring now to the drawings and particularly with reference to Fig. 3, I provide an elongated ellipsoid body of some very light metal such as magnalium, as indicated at 1 and provided on the bottom side thereof 50 nearly amidship is an axle 2 on which is mounted a pair of wheels 2' supported by posts 2", which together with the wheels serve as a landing gear. To the rear of the axle 2 is mounted a skid shoe which extends toward the rear of the body at a curved inclination as shown. On the top of the body is a low observation tower 4 provided with a plurality of transparent windows 5 and a pair of benches 6. The reference numeral 7 55 indicates a trap door arranged above steps 8, to the cock-pit where the principal operator or pilot sits. This operator's seat 9 is positioned whereby ready access may be had to a wheel 10 and a pedal 11, an arm of which shifts a link 11" to actuate an idle gear of a clutch which controls the main shaft 13. The engine 12 may be of any desired type controlled in the usual manner for operating a pair of gears on a main shaft 13 for controlling the propelling mechanism of the aeroplane. Geared to the main shaft 13 is a crank shaft 14 and the main shaft operates a pair of spur gears controlling the main propeller 15 and also operates a pair of auxiliary 60 propellers 16, 16", the latter being symmetrically placed at the sides of the main propeller. The gear 17 may have a desired speed ratio with reference to the main propeller shaft which is directly driven by the gear 18, while a pair of bevel gears 19 are provided for each of the auxiliary propellers 16, 16", which may be driven at any preferred speed ratio. The clutch referred to includes an idle gear 22" that is movable to be thrown into and out of mesh with respect to a gear 21" secured to the main shaft. The clutch mechanism is shown in detail in Fig. 7 and the pedal 11 acts on a pivoted arm 11" a main arm 11" and the link 11" to shift the gear 65 70 75 80 85 90

22^a as above set forth. When pressure on pedal 11 is relieved the helical spring 22^d puts the gear 21^a in mesh with the gear 22^a that is driven by the motor shaft. The engine may be supported on a pair of ribs 23 bolted longitudinally of the body of the aeroplane and the main shaft has bearings formed in the intermediate ones of vertical struts 24, 24^a, 25^a. On the crank shaft 14 is mounted a disk crank 26 connected by a universal joint with a lever 27 pivoted in the tail of the body of the aeroplane and connecting by a link to a fin or auxiliary propeller 28^a which is driven by the disk 26 for causing a rapid reciprocatory motion thereof over a short arc which gives a forward directive movement to the aeroplane, and is similar somewhat to the action of the tail of a fish.

The lifting moment of the aeroplane is effected by two pairs of reciprocable wings 29, 29^a, 30 and 30^a which are driven by the cranks 31 and 31^a on the crank shaft 14 and which operates cross heads 32, giving a vertical reciprocatory movement to the wings. Each wing is provided with a socket portion 29^b pivoted to the cross heads and in which the wing element is rotatably supported. Each wing member is provided with a flanged spool 34 over which is wound a chain 36 which traverses pairs of wing elements and is guided through tubes 36^a and over pairs of sheaves, 36^b, for connection with the shaft of the wheel of the main pilot as will be evident from an inspection of Fig. 3. Thus the wings are rapidly reciprocable by the cross-heads and may be inclined at an angle or feathered at the option of the pilot to vary the lifting moment. The assistant operator who sits forward of the main operator has control of a wheel 37 on the shaft of which is secured and wound reversely a pair of control chains 40 secured to flexible cables 37^b that are attached to a pair of ailerons 35, 35^a mounted in brackets on the sides of the body, and these ailerons are retracted by a pair of springs 38 and 38^a one for each aileron and which have their ends secured thereto and the body respectively as best shown in Figure 1 of the drawings, so that upon operation of the wheel 37 the ailerons are moved or shifted on their pivots so as to divert the line of motion of the aeroplane as will be apparent.

The chains 40 are guided through tubes 41 which terminate at their rear ends adjacent the seat 9 and secured to the chains 40 are handles 42 arranged in convenient reach of the operator in the seat 9, whereby the ailerons can be controlled by the main operator when necessary or desired. By the arrangement of the respective operators' seats, the auxiliary operator is under the eyes of the main operator or pilot and indicating vanes 37^a are connected to the controlling elements of the ailerons whereby either of the operators can as-

certain by glancing at the indicating vanes 37^a the position of the ailerons.

It will thus be apparent from the foregoing that the main operator or pilot controls the forward and lifting movement of the aeroplane or aerial device, while the auxiliary pilot may control the directional movement thereof through the medium of the ailerons. The propellers 15, 16 and 16^a as well as the fin 28^a and wings, propel the machine forward and upward, and the wings may be shifted so as to offer no resistance when desired, through the mechanism above set forth and clearly shown in Figure 3.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An aerial device comprising a hollow elongated ellipsoid body, a main and a pair of symmetric auxiliary propellers at the prow thereof, means for operating them simultaneously for propulsion, variable controllable ailerons to control the direction of movement of the device and a vibratory shaft driven tail to assist propulsion thereof.

2. An aerial device comprising an elongated hollow ellipsoidal body, a main propeller, a symmetrical pair of auxiliary propellers, and a vibratory fin at the tail mounted on a vertical axis.

3. An aerial device comprising an elongated hollow magnalium ellipsoid body, a main propeller, a pair of symmetrically arranged auxiliary propellers, said propellers being disposed forwardly of the body, means for operating the propeller, pairs of wings extending laterally from said body, means for operating and controlling the wings, said last mentioned means including means for feathering the wings, a vibratory power driven fin to assist the propellers and arranged at the rear of the body, a pair of spring retracted ailerons arranged laterally adjacent the rear of the body and means actuating the ailerons against the tension of the springs thereof.

4. An aerial device comprising an elongated hollow ellipsoid shape body, a drive shaft mounted in bearings in said body, a motor arranged in said body, clutch means between the drive shaft and motor for controlling the drive shaft, a main propeller geared to the drive shaft and extending forwardly from said body, auxiliary propellers extending upon opposite sides of the main propeller and below the same, said auxiliary propellers being geared to the drive shaft, a crank shaft geared to the drive shaft, a disk secured to the rear end of a crank shaft, a fin mounted for reciprocatory movement and ar-

ranged through the rear end of the body,
means for reciprocating said fin from said
disk, cross heads having connection with the
cranks of the crank shaft, wings pivotally
5 mounted and rotatably associated with respect
to the cross heads, means for feathering said
wings, ailerons pivotally secured to said body,
springs having one of their ends secured to
said body and ailerons respectively for nor-
10 mally holding said ailerons in one position,
and means for operating said ailerons against
the tension of said springs.

In testimony whereof I affix my signature.
PABLO ESCOBEDO.
